12 Claims

ABSTRACT OF THE DISCLOSURE

A slurry explosive composition comprising at least one inorganic oxygen-supplying salt, a solvent, a thickener, a fuel and as a density control agent, N,N'-dinitrosopentamethylenetetramine.

This invention relates to slurry explosive compositions comprising a gas blowing agent for adjustment of the density to improve their sensitivity. The invention also relates to a method of manufacturing such explosives.

Explosive compositions comprising an oxygen-supplying salt, for example ammonium nitrate, and a sensitiser and/or fuel together with a fluid solvent, disperser or carrier such as water, are known. These compositions are commonly referred to as slurry explosive compositions or, more generally, as slurry explosives. Such slurry explosives may range in degree of firmness or consistency from highly viscous, plastic-like extrudable compositions to less viscous, pumpable or pourable fluid-like mixtures.

Slurry explosive compositions of the aforementioned types normally contain as essential ingredients widely known sensitising and power-enhancing materials and fuels, for example finely divided light metal or finely divided carbon. In some cases it is advantageous to add a self-explosive ingredient such as particulate trinitrotoluene (TNT), pentaerythritol tetranitrate (PETN) or smokeless powder to further improve the sensitivity or strength or both of the slurry explosives and thereby ensure detonation and propagation. Generally, the oxygen balance of the total composition is within the range +15 to —35 g. of oxygen per 100 g. of finished explosive. A wide range of such compositions is known to the art.

It is well known in the art that the sensitivity of slurry explosives may be controlled by controlling their densities. Further, controlled variations in density without any major change in a formulation are advantageous under certain conditions in achieving optimum blasting results. A number of density lowering agents and methods of aeration are already known in the art, but the reduced density effected thereby is, in general, not maintained over prolonged storage.

It is an object of this invention to provide a means of controlling the sensitivity of slurry explosives and to provide slurry explosives which will maintain their sensitivity on storage.

It has now been found that the density and sensitivity of slurry explosives can be advantageously controlled by incorporating N,N'-dinitrosopentamethylenetetramine in the composition. The explosives maintain their sensitivity over long storage periods.

Thus, in accordance with this invention a slurry explosive composition comprises at least one inorganic oxygen-supplying salt, a solvent for the said salt, a thickener for the solution of the said salt in the said solvent, a fuel and, as a density control agent, N,N'-dinitrosopentamethylenetetramine.

Preferably the N,N'-dinitrosopentamethylenetetramine is present in an amount in the range 0.01 to 1% by weight of the composition.

2

Preferred slurry explosive compositions of the invention contain 15 to 83% by weight of at least one inorganic oxygen-supplying salt, 10 to 30% by weight of solvent, 0.2 to 2.5% by weight of thickener, 5 to 55% by weight of fuel and 0.01 to 1% by weight of N,N'-dinitrosopentamethylenetetramine.

The density of the composition can be varied over a wide range by varying the proportion of the N,N'-dinitrosopentamethylenetetramine, only a small proportion being required for a substantial reduction in density.

The inorganic oxygen-supplying salt may conveniently comprise a nitrate of ammonia, sodium, potassium, barium or calcium or a mixture of two or more of said nitrates;

The solvent preferably comprises water, formamide, dimethylsulphoxide, ethylene glycol or mixtures thereof.

The fuel may conveniently comprise particulate light metal or metalloid, for example, finely divided aluminium, aluminium alloy, silicon, ferrosilicon, ferrophosphorus, particulate organic explosive, organic nitrate, for example isopropyl nitrate, sulphur, or carbonaceous material, for example, carbon, urea, thiourea or sugar or a mixture thereof.

Useful particulate organic explosives which may be used in the compositions include, for example, TNT, PETN, cyclotrimethylenetrinitramine (RDX), Composition B (mixture of TNT and RDX), Pentolite (mixture of PETN and TNT), smokeless powder, nitrocellulose, nitrostarch and mixtures of these.

In aqueous slurry explosive compositions the thickener may conveniently comprise mannogalactans, for example guar gum or carob seed gum. Where dimethylsulphoxide or formamide is employed alone as the solvent, hydroxyethyl cellulose may be used as the thickener. Where dimethylsulphoxide is used in combination with water, guar gum, tamarind flour or starch are suitable thickeners.

The composition may also advantageously comprise cross-linking agents to cross-link the thickener. Suitable cross-linking agents for the polysaccharides in aqueous slurry compositions include pentavalent antimony compounds, for example potassium pyroantimonate, or metallic chromates and dichromates, for example zinc chromate, sodium dichromate or potassium dichromate, advantageously in conjunction with a soluble antimony compound, for example potassium antimony tartrate.

Other additional ingredients commonly used in explosive compositions, for example stabilisers, may be included in the composition as desired.

The invention also includes a method of preparing a slurry explosive wherein N,N' - dinitrosopentamethylenetetramine is mixed into an acidic slurry explosive composition as a density control agent. The rate of reduction of density by the said aerating agent can be controlled by the pH of the slurry explosive. The lower the pH, the higher is the rate of reduction of density, but the eventual extent of density reduction depends only upon the quantity of N,N'-dinitrosopentamethylenetetramine used. The pH is preferably in the range 3 to 6 and more preferably in the range 4.5 to 5.5.

The composition may, for example, be acidified by zinc nitrate or if the pH is already undesirably low it may, for example, be raised by ammonium hydroxide or an amine.

The invention is further illustrated by the following examples in which all parts and percentages are by weight. Examples 1, 3, 6 and 8 contain no N,N'-dinitrosopentamethylenetetramine and were included for comparison.

EXAMPLES

In these examples the following mixing procedure was adopted.

The oxygen supplying salt, solvent and fuel were mixed in a ribbon mixer till a homogeneous solution or suspen-

sion was obtained. The pH of the mixture was adjusted as described by addition of zinc nitrate or ammonium hydroxide. Guar gum predispersed in ethylene glycol was then added to the mixture and mixed until a thick gel was obtained. The requisite quantity of N,N'-dinitropentamethylenetetramine (as sold under the trade name Vulcace BN by Imperial Chemical Industries Limited), cross-linking agent and stabilisers were then added and mixed till a homogeneous mix was obtained.

The sensitivity of the slurry explosive compositions was tested by determining the minimum charge of a series of test explosive charges required to initiate detonation in 12 inch long cartridges of the compositions having the diameter indicated. The test explosive charges in ascending order of strength were:

No. 6 Detonator: 0.3 g. PETN base charge

No. 8 Detonator: 0.5 g. PETN base charge

Anstart: 1.5 g. PETN charge

Pentolite primer: 10 g. Pentolite (50/50 PETN/TNT)

The density was measured as the bulk density.

Details of the compositions and properties are given in the following tables:

Table 1 shows the effect of incorporation of various proportions of N,N'-dinitrosopentamethylenetetramine on density and sensitivity of two compositions containing no self explosive sensitiser.

Table 2 shows the effect of incorporation of N,N'-dinitrosopentamethylenetetramine on density and sensitivity of a composition containing a self explosive sensitiser.

Table 3 shows the storage properties of three typical slurry explosive compositions containing N,N'-dinitrosopentamethylenetetramine without self-explosive sensitiser.

Table 4 shows the effect of pH on the rate of reduction of density of a typical slurry explosive containing N,N'-dinitrosopentamethylenetetramine without self - explosive sensitiser.

What we claim is:

1. A slurry explosive composition comprising at least one inorganic nitrate, a solvent for the said inorganic nitrate, a thickener for the solution of the said inorganic nitrate in the said solvent, a fuel and, as a density control agent N,N'-dinitrosopentamethylenetetramine.
2. A composition as claimed in claim 1 containing 15 to 83% by weight of at least one inorganic nitrate, 10 to 30% by weight of solvent, 0.2 to 2.5% by weight of thickener, 5 to 55% by weight of fuel and 0.01 to 1% by weight of N,N'-dinitrosopentamethylenetetramine.
3. A composition as claimed in claim 1 wherein the inorganic nitrate is selected from the group consisting of the nitrates of ammonia, sodium, potassium, barium or calcium and mixtures of two or more of said nitrates.
4. A composition as claimed in claim 1 wherein the solvent is selected from the group consisting of water, formamide, dimethylsulphoxide, ethylene glycol and mixtures thereof.
5. A composition as claimed in claim 1 wherein the fuel is selected from the group consisting of particulate light metal, particulate organic explosive, organic nitrate, sulphur and carbonaceous material.

6. A composition as claimed in claim 5 wherein the fuel is selected from the group consisting of aluminum, aluminium alloy, silicon, ferrosilicon, ferrophosphorus, carbon, urea, thiourea, sugar, isopropyl nitrate, trinitrotoluene, pentaerythritol tetranitrate, cyclotrimethylenetrinitramine, smokeless powder, nitrocellulose, nitrostarch and mixtures of two or more thereof.

7. A composition as claimed in claim 1 wherein the thickener is selected from the group consisting of guar gum, carob seed gum, tamarind flour, hydroxyethyl cellulose and starch.

8. A composition as claimed in claim 1 comprising as a cross-linking agent for the thickener, a compound selected from the group consisting of pentavalent antimony compounds, metal chromates and dichromates.

9. A composition as claimed in claim 8 wherein the cross-linking agent comprises a compound selected from the group consisting of metallic chromates and dichromates in conjunction with a soluble antimony compound.

10. A composition as claimed in claim 9 wherein the soluble antimony compound is potassium antimony tartrate.

11. A method of preparing a slurry explosive which comprises mixing an acidic slurry explosive composition comprising an inorganic nitrate, a solvent for the inorganic nitrate, a thickener for the solution of the inorganic nitrate in said solvent, and a fuel with N,N'-dinitrosopentamethylenetetramine, as a density control agent, at a pH in the range of 3 to 6.

12. A method as claimed in claim 11 wherein the pH of the slurry explosive composition is adjusted by the addition of zinc nitrate, ammonium hydroxide or an amine.
